HYDRAULIC IMPACT PULSATR TRANSMISSION SYSTEM

Charles F. Warren, deceased, late of Paragould, Ark., by Kathleen Warren, executrix, Paragould, Ark., assignor to Charles F. Warren, Jr.

Original application April 12, 1946, Serial No. 661,542, now Patent No. 2,676,464, dated April 27, 1954. Divided and this application April 21, 1954, Serial No. 424,629

6 Claims. (Cl. 60—54.6)

The invention relates generally to hydraulic impact pulsator transmission systems and more particularly to a system adapted to transmit impacts by means of a reciprocating column of fluid. It is the general object of the invention to provide a new and improved system of this character.

This is a division of application Serial No. 661,542, filed April 12, 1946, for Patent 2,676,464, upon a Hydraulic Impact Pulsator Transmission System.

Another object is to provide a hydraulic impact transmission system for use with portable impact tools; and particularly one having a conduit between an impact producing unit and an impact tool unit, means in the impact unit for filling the conduit with a fluid (as for example, oil or other suitable liquid) and for maintaining a column of fluid in the conduit under static pressure, means for imparting rapid reciprocating movement to the rigid column so formed, and means at the impact tool unit end of the conduit forming a restricted return outlet for excess fluid supplied to the conduit. A further object is to provide such a system with manually operable means at the impact tool unit for enlarging the return outlet for the fluid so as to relieve the pressure on the column and stop the operation of the tool.

Another object is to provide an impact transmission system with an impact producing unit, an impact tool unit and pressure fluid supply and return conduits connecting the impact unit with the impact tool unit, together with control means carried on the tool unit for starting and stopping the operation of the tool when the impact unit is in operation.

Another object is to provide a new and improved impact tool unit for transmission system.

A further object is to provide a new and improved hydraulic impact transmission system embodying a reciprocable rigid column of fluid, means for reciprocating the column, means connected to one end of the column for supplying fluid thereto at a rate in excess of the leakage therefrom, and means at the other end of the column for controlling the discharge of excess fluid therefrom.

Other objects and advantages will become readily apparent from the following detailed description taken in connection with the accompanying drawings in which:

Fig. 1 is a perspective view of a preferred form of the invention.

Fig. 1a is a perspective view thereof on a reduced scale with two impact tool units.

Fig. 2 is a vertical section approximately along the line 2—2 of Fig. 3 of the pumping unit thereof.

Fig. 3 is a plan section along the line 3—3 of Fig. 2.

Fig. 4 is a vertical section on a reduced scale along the line 4—4 of Fig. 2.

Fig. 5 is a vertical central section through the impact tool unit.

Fig. 5a is an enlarged fragmentary view of a portion of Fig. 5.

2

Fig. 6 is a fragmentary section along the line 6—6 of Fig. 5.

Fig. 7 is a similar fragmentary section with the control valve in an alternative position.

5 While the invention is susceptible of embodiment in many different forms, there is shown in the drawings and will herein be described in detail one such embodiment, with the understanding that the present disclosure is to be considered as an exemplification of the principles of the invention and is not intended to limit the invention to the embodiment illustrated. The scope of the invention will be pointed out in the appended claims.

In the form selected for purposes of disclosure this invention is embodied in a hydraulically actuated impact tool system comprising generally a pumping or impact producing unit A (Fig. 1), an impact tool B, a supply conduit C connecting the pumping unit to the impact tool for conducting a fluid (such as oil) under pressure to operate the impact tool and a return conduit D for returning excess operating fluid to the pumping unit. As shown in Fig. 1a a pair of impact tool units B are connected to an impact producing unit A, the unit A and a drive motor E therefor being mounted on a common frame F. As shown, a belt G runs from a pulley 25 on the motor to a pulley H on the drive shaft of the unit A.

Impact tools of the character to which this invention relates are in the nature of hammers, drills and tampers, which are similar in function to corresponding pneumatically driven tools. However, such tools of the pneumatic type require the provision of an air compressor unit accompanied by an internal combustion motor or other prime mover of substantial power, whereas the combination of an impact unit or pump and an impact tool directly connected to the pump by means of a flexible conduit which confines a continuous and rigid column of fluid under pressure extending from the pump to the tool, constitutes a much more efficient mechanism and employs only a fraction of the power of the pneumatic system for driving the pump and operating the tool. The present invention is an improvement in hydraulic impact transmitting systems of the type embodying a rigid reciprocable column of oil (or other liquid) and constitutes an improvement in the system of Patent No. Re. 22,122, issued to Charles F. Warren and William R. Smith, dated June 16, 1942.

In the form illustrated the pumping unit is adapted to operate two impact tool units. The operating elements of the pumping unit are mounted in a housing 1 which serves also as a reservoir for the hydraulic fluid, and as seen in Fig. 1 is of substantially rectangular form except that the top wall 2 and one end wall 3 are connected by a curved portion 4 substantially concentric with the axis of a drive shaft 5. This shaft extends through a hollow boss 6 in one side wall of the housing, and the boss 6 provides a pocket or recess 6a which seats the roller bearing 7 for the shaft together with a packing element 8. A circular opening 9 in the opposite side wall of the housing is large enough to permit insertion or withdrawal of the shaft 5 with its driving eccentric 10, 10 together with the bearing assembly; and this opening 9 is closed by a cover plate 11, which includes an inwardly open pocket or recess 11a to support a roller bearing 12 for the inner end of the shaft 5. Each of the eccentrics 10 carries a ring 13 confined between a flange 10a and a retainer ring 10b with interposed bearing rollers 14, so that the eccentric may turn freely within the ring 13. Thus in the process of assembly, the shaft 5, with its bearings 7 and 12 in place and with its eccentrics 13 fitted with their rings 14, may be inserted as a unit through the opening 9, and its mounting in the housing will be completed by application of the cover

Application July 23, 1957, Serial No. 673,720

1. Claim. (Cl. 61—39)

This invention relates to masonry structures and to methods of producing structural members from monolithic stone bodies of the class including granite and other natural stones which are removed from their original geological formations.

Structural materials of the natural stone class, such as are exemplified by granite in particular, although characterized by great inherent compressive strength, exceedingly fine weathering characteristics, and complete absence of compressive creep and shrinkage, do not have the tensile strength characteristics which may be desired in some structural members. Therefore, it has not been practical to utilize granite in structures which are subjected to bending moments that produce a net tension across a monolithic body, or across joint planes of abutment of a composite stone structure.

It is the object of the present invention to provide improved load bearing characteristics in structural members of monolithic stone and to devise improved methods of forming structural members of the natural stone class. Specifically, it is an object to provide monolithic stone structural members which are characterized by the utilization of the superior compression properties of the natural stone without the introduction of major tensile stresses in the natural stone.

It is also an object of the invention to devise composite structural members made up of a plurality of monolithic pieces of natural stone wherein the combined mass is subjected to mechanically induced compression forces.

These and other objects will be more fully understood from the following discussion and disclosure of the invention.

From a study of the inherent tensile strength limitations of a monolithic stone body employed as a structural member and having in mind the foregoing objectives, there has evolved the inventive concept of re-establishing in a monolithic stone body a part of the compression originally present in the stone body as it occurred naturally in its geological formation. This concept further includes the idea of exerting compression forces within the monolithic stone body of a predetermined value so as to obtain a structural member whose load bearing capacity is a direct function of the total recompression introduced into the monolithic stone body.

It is comprehended, as a general proposition, that the natural compression forces originally occurring in monolithic natural stone have, when partially re-established in a monolithic natural stone structure, a direct bearing on the load carrying capacity of said structural member. However, the precise magnitude of the original compressive stresses in the natural stone in its geological formations is unknown and therefore the limitations on re-introduction of compressive stresses are given by way of opinion but may well extend to the ultimate compressive strength of the natural stone.

We have found that this concept may be implemented by making use of well known devices, such as high tensile steel stressing elements. In this connection, a monolithic

2

stone body is, in accordance with the invention, formed with an opening of predetermined size and location. In this opening is placed a stressing element, such as a steel tendon, which is thereafter subjected to a suitable tensioning force and held in tension by anchoring means on opposite sides of the stone body. There is then accomplished a recompressing of the stone with the desired change in the load bearing capabilities of the natural stone structure. A change is found also in the modulus of elasticity of the natural stone. Unlike the well-known stress-strain curve for a material such as concrete, where the compressive modulus elasticity decreases with stress throughout a range of increasing stress values, the re-establishment of compression in a compressed natural stone body which has been subjected to decompression results in the monolithic stone body having a compression modulus of elasticity which increases with stress throughout a range of stress values. Similarly, other desirable changes are obtained, as appears from the following detailed discussion of the invention.

In the accompanying drawings,

Fig. 1 is a side elevational view illustrating a structural member supported in a transversely extending position with a load supported thereon;

Fig. 2 is another side elevational view showing a transversely supported structural member of the invention, and further indicating a modified form of restressing element location;

Fig. 3 is a cross-sectional view taken on the line 3—3 of Fig. 2 and further indicates a bonding agent for anchoring the restressing element, solidly in the structural member;

Fig. 4 is a detailed view showing the opening formed in the structural member for receiving the restressing element;

Fig. 5 is another side elevational view illustrating a transversely supported structural member made up of a plurality of pieces of monolithic stone secured together by means of a restressing element;

Fig. 6 is a graph showing the curve for the stress-strain relationship of the compression component of a load bearing member such as that illustrated in Fig. 1. This figure also contains a comparative curve for the stress-strain relationship present in a concrete load bearing member of similar construction;

Figs. 7, 8 and 9 illustrate a specific adaptation of monolithic type load bearing members of the invention employed in a retaining wall construction;

Figs. 10, 11 and 12 illustrate a load bearing member supported on monolithic stone columns secured together in compressed relationship;

Fig. 13 is a diagrammatic view showing a monolithic beam provided with a plurality of restressing elements extending in different directions; and

Fig. 14 is a perspective view illustrating a surface plate made up of a plurality of monolithic stone bodies held together by means of restressing elements which have been tensioned to a predetermined degree.

Referring first to the structural member shown in Fig. 1, numeral 2 denotes a monolithic stone body, such as granite, which has been removed from its original geological formation by quarrying and subsequent finishing operations. In its original state, this monolithic stone body was under very heavy compressive forces of an order of magnitude of 5000 pounds per square inch and greater. It is pointed out that, during the process of separating the stone body from a large mass of which it was a constituent part, there necessarily took place a relieving of stresses in the bed rock and the stone body, when finally removed, was, therefore, in a decompressed state.

In accordance with the invention, the structural member 2 in the decompressed state described is formed with

an opening 4, as by drilling or other suitable means. In this opening, there is located a restressing element 6 which may, for example, consist of a steel tendon. The tendon is then subjected to tensioning forces of some suitable magnitude and held by means of anchoring devices as 8 and 10 located on two opposite external surfaces of the structural member 2. Although not necessarily so, it may be desired to place this stressed tendon 6 in a position such that it is nearer one side of the structural member 2 than the other.

As an example of one specific tensioning force which may be used, there may be cited a force of 100,000 pounds which, in one case, was applied to a rectangular beam having a cross-sectional area of 120 square inches. This structural member may then be supported in the manner suggested in Fig. 1 on spaced-apart abutments 12 and 14 and subjected to the weight of a load 16. The binding stresses developed by this arrangement would normally induce compressive stresses at the upper surface of the natural stone component of this structural member and tensile stresses at the lower surface 2b. However, by recompressing the natural stone before any working loads are applied, the entire stress distribution is altered and the natural stone acts only in compression. By utilizing only the compressive properties of the natural stone, its load carrying capacity is greatly increased to a point where the application of monolithic stone for a substantial span in a beam member of this type becomes practical and capable of supporting relatively heavy loads such as are represented by the load 16 suggested in Fig. 1.

In Fig. 6, there is illustrated graphically the stress-strain curve for granite when employed in a manner such that it is subjected to compressive stresses. As will be apparent from an inspection of Fig. 6, the secant modulus for this granite member increases with increased stress all the way through a range of stress values starting at zero and running up to a point of failure. This differs remarkably from a similar stress-strain curve for standard concrete which, as shown in Fig. 6, falls away rapidly after a very slight rise in the stress range.

In Fig. 2, there is illustrated a monolithic stone structural member 20 in which is located a stressing element 22 which is arranged in a curved path, as shown. This arrangement is designed to provide a more favorable stress distribution at the ends of the structural member while providing adequate resistance to bending stresses which are maximum at the center of the member.

Fig. 5 discloses another arrangement in which a plurality of pieces of monolithic stone 23, 24, 25, and 26 are secured together in abutting relationship by means of a stressing element 28. This member not only secures the pieces together but also provides a recompression force which imparts a more favorable load bearing characteristic to this structural member, particularly with respect to the load 30.

In Figs. 7-9, inclusive, we have further illustrated a somewhat more specific adaptation of the invention in the form of a prestressed granite masonry retaining wall. It will be understood that the dimensions of such a wall are, in general, governed by the height of the bank which is to be retained as well as the allowable bearing pressure of the soil in the bank. In this particular form of the invention, a plurality of granite ashlar pieces are combined with prestressed granite counterforts supported on a suitable concrete footing and preferably surmounted by a granite cap.

In the structure shown, numeral 50 denotes the concrete footing on which is mounted a plurality of ashlar pieces as 51, 52, 53, etc., and these ashlar pieces constitute one section of a retaining wall facing. A second tier of ashlar pieces as 54, 55, 56, also supported on the concrete footing 50, are spaced apart by the granite counterfort 58 which consists of a vertical granite body having inclined surfaces as 58a and 58b. A granite cap 60 is received on the top of the tiers of ashlar pieces.

In accordance with the invention, we further impart stability to the counterfort 58 by the use of tensional high strength steel tendons as 62 and 64 which are embedded in the concrete footing at their bottom ends and which are located through the upper end of the counterfort 58 and anchored at points 62a and 64a. The tendons may also be arranged at an angularly disposed position, as shown. If desired, the granite cap 60 may be recessed to provide protective enclosures immediately surrounding the anchor elements 62a and 64a. The ashlar pieces are designed to act as a beam in each of the tiers with all horizontal earth forces being transmitted to the restressed counterforts by means of steel dowels as 70, 71 and 72 which are disposed in the manner suggested in Fig. 8.

In Figs. 10, 11 and 12, we have illustrated still another specific combination of structural components including a girder member 80 which may be supported on granite columns indicated by the arrows 81 and 82 made up of two tiers of ashlar pieces, as shown in Fig. 10. The tiers may be supported on a concrete footing 84. In this particular arrangement, the tiers of ashlar pieces constituting vertical column members are prestressed by means of tensioned steel tendons as 86 and 88 which extend vertically through the ashlar pieces, as shown in Fig. 12, and may be anchored between the girder 80 and the concrete footing 84. Fig. 12 shows a similar arrangement involving the use of a larger number of steel tendons as 90, 92, 94 and 96. In this arrangement, a pair of steel tendons are run all the way through the granite cap 98 while the remaining pair of tendons are arranged to exert compressive forces at opposite sides of respective ashlar pieces along lines of holding which extend externally of the granite cap.

In Fig. 13, there has been illustrated a jointed stone beam made up of sections 100, 101 and 102 which are held against one another by means of a prestressed steel tendon 104. The beam may further be provided with transverse tendon elements as 106 and 108.

In Fig. 6, we have illustrated still another adaptation of prestressed granite in the form of a tool consisting of a jointed natural stone surface plate which may consist of a bed for machine ways. In this form of the invention, a plurality of granite pieces as 110, 112, 114, 116, are secured together by means of prestressed steel tendons as 118, 120, 122, 124 and 126 and these tendons may be stressed in some predetermined amount which will furnish a restressing of each of the granite components in a desired degree to withstand certain working loads to which the surface plate may be subjected or to resist dimensional change from other conditions.

The several different forms of prestressed granite structural arrangements of the invention which have been disclosed furnish a number of outstanding advantages in comparison with concrete. For example, concrete "creeps." For instance, a body of concrete under a given load will, after a period of time, show a very substantial increase in the deformation which is present initially on receiving the load. As the period of time increases, the amount of deformation may grow appreciably greater.

In the case of granite, the curve of deformation produced by plotting a stress-strain factor against time is substantially a straight line indicating that there is no change in deformation at anytime.

A necessary result of so-called "creep" present in concrete is the definite tendency for a loss in the steel tendon prestressing force which may be utilized in any given instance. This loss can be directly traceable to "creep" to an extent of about 10% of the original tension force exerted in the steel tendon. Thus, in the case of concrete, a substantial loss in prestressing force will be experienced whereas, in the case of a granite structural member, the prestressing tendon will lose none of its intensity since there is no "creep" in the granite. It follows necessarily, therefore, that, with granite, it is possible to use ap-

proximately 10% less steel in the tendon specifications since it does not lose its effectiveness as it does in concrete.

A further advantage of the prestressed granite of the invention is present from the degree of control which can be realized. In the case of poured concrete, it is impossible to be sure of the exact strength produced by any given mix and it is customary to wait for a period of from several days up to a month to determine the strength of any given mix. In contrast, the granite which may be thought of as having been already formed and cured in nature can be tested at anytime and its strength known precisely before its installation.

In this same connection, there is realized a further advantage in that a monolithic granite structure can take a full load as soon as it is tensioned and supported, whereas, with concrete, it is necessary to wait a considerable period of time to strip the forms in which the concrete is poured and to allow the concrete to fully set, which may take as long as a month.

For the foregoing reasons, therefore, it will be apparent that we have disclosed a novel and useful structural material and method of producing a prestressed stone body made up of one or more component parts. These structural components may be embodied in various types of structural combinations to impart various advantages for each specific application.

While we have shown preferred embodiments of the invention, it should be understood that various other changes and modifications may be practiced within the scope of the appended claim.

Having thus described our invention, what we claim is:

A monolithic natural stone structure for use as a retaining wall comprising in combination a base, a plurality of tiers of stone components mounted on the base, counterfort members of stone having a compressibility characteristic resulting from the stone members having been subjected to and relieved from earth pressure and extending vertically upwardly between each of said tiers, a plurality of prestressed steel tendons anchored on the base and secured to the upper portions of the said counterforts and means for interlocking the said tiers of stone components with the counterforts, said prestressed tendons being arranged at an angle to the vertical center line of counterforts and operating to place the counterforts in a state of compression and resist horizontally acting earth forces.
